(57) **CLAIM**

The ornamental design for a pellet press, as shown and described.

DESCRIPTION

FIG. 1 is a perspective view of a pellet press, showing our new design from the front, top and left side;
FIG. 2 is a right side view thereof;
FIG. 3 is a top plan view thereof;
FIG. 4 is a front elevational view thereof;
FIG. 5 is a bottom plan view thereof;
FIG. 6 is a left side thereof; and,
FIG. 7 is a rear elevational view thereof.
The broken lines in the drawings depict unclaimed environmental subject matter.
